United States Patent Office

Des. 192,610
Patented Apr. 17, 1962

192,610

STRAW DISPENSER

Jerome Berghoff, 640 Hightree Road,
Pacific Palisades, Calif.

Filed Nov. 3, 1961, Ser. No. 67,374

Term of patent 14 years

(Cl. D52—2)

FIG. 1.

FIG. 2.

FIG. 3.

FIG. 4.

FIG. 1 is a perspective view of a straw dispenser embodying my new design;

FIG. 2 is an end elevational view of this straw dispenser;

FIG. 3 is a side elevational view of this straw dispenser;

FIG. 4 is a top plan view of this straw dispenser.

The undisclosed side and end of the straw dispenser are substantially the same in appearance as the side and end shown.

I claim:

The ornamental design for a straw dispenser, substantially as shown and described.
